AMUSEMENT DEVICE

Moses Goldman, Brooklyn, N. Y.

Application February 7, 1938, Serial No. 189,250

3 Claims. (CL 273—104)

This invention relates to amusement devices and more particularly to combinations of games of skill especially of the type comprising a hoop and target and a new and improved score displaying mechanism associated therewith.

It is a major object of the present invention to provide an amusement device comprising a game of skill of the type consisting of a combination of hoop or hoops and a target upon which the hoops are caught when tossed, and a new and improved score displaying mechanism whereby after a hoop or a plurality of hoops have been tossed upon the target the number thereof and the relative positions thereof upon the target will be visibly displayed.

It is another object of the present invention to provide an amusement device including means for receiving a plurality of hoops when tossed upon a relatively stationary member, whereby the hoops can be received and positioned in a plurality of places along said member, and means for visibly displaying the number and locations of hoops so positioned.

It is also an object of the present invention to provide an amusement device comprising a relatively stationary standard toward which a plurality of hoops are thrown and upon which said hoops can be positioned in at least several localities, combined with an electrical circuit wherein means are provided for visibly and/or audibly indicating the number and/or positions of hoops so positioned on said member.

It is a further and additional object of the present invention to provide a novel type of switching means whereby an electrical circuit can be controlled through the tossing of electrically conductive hoops upon a standard or a member, thereby effecting the completion of one or several of a plurality of electrical circuits associated with said member.

Other objects, advantages and features of the device according to the present invention will be apparent to those skilled in the art during the course of the following description wherein a specific embodiment of the present invention, herein illustrated, will be described, it being clearly understood however that the illustrated preferred embodiment is given solely by way of example and is non-limitative.

In the drawings:

Fig. 1 is substantially a perspective view of the now preferred embodiment of the present invention;

Fig. 2 is substantially a side elevational view of a portion of the structure illustrated in Fig. 1,

showing the hoop receiving member and a portion of the score displaying apparatus;

Fig. 3 is a vertical sectional view of the front end portion of the hoop receiving member;

Fig. 4 is a sectional view of Fig. 3 taken along the line 4—4; and

Fig. 5 is a partially schematic electrical circuit diagram showing the presently preferred circuit utilized in the device illustrated in Fig. 1.

Regarded in certain of its broader aspects, the present invention comprises a substantially vertical but slightly inclined annulus having a serrated relatively horizontal member positioned in the center thereof, said serrated member comprising a plurality of switch elements associated with visual and audible score indicating means whereby electrically conductive hoops resting upon serrations in said member actuate said means.

In certain of its less broad aspects and, indeed, in its preferred embodiment the present invention comprises an annulus and member arranged as hereinabove described, wherein syncategoretically a plurality of synclined surfaces are provided on said member, one of each pair of surfaces being associated with a common line and the other of each pair of surfaces being associated with visual and audible score indicating means whereby a metallic annulus positioned upon said synclined surfaces, resting upon said edges, results in actuation of said visual and audible score indicating means.

In order to facilitate a fuller and more complete understanding of the present invention the herein illustrated embodiment thereof will be hereinafter described.

Referring now to Fig. 1, wherein a perspective view of the device is shown, the annulus 10 and serrated hoop receiving member generally designated at 11 are shown supported by means generally designated at 12.

The supporting means comprise a pair of anti-clined composite legs 13 and 14, forming the front support, and another pair of composite legs 15 and 16 forming the rear support. It will be noted that each of these legs comprises a pair of interconnected members each provided with a plurality of openings, some of which are designated at 17, the openings in adjoining members being alignable whereby fastening means, for example bolts, some of which are designated at 18, can be passed therethrough, thereby substantially firmly but adjustably securing said members in cooperative relation. In the preferred embodiment of the invention, the lowermost portions or feet 55

of these support members are provided with rubber tips 19, substantially as shown. It will be observed that the upper portions of the front supporting members 13 and 14 are attached directly to the annulus 10 and that the upper portions of the rear supporting legs 15 and 16 are attached by means including hinges (not shown) to an upper portion of the score indicating board generally designated at 20. Stability of the device 10 is preferably enhanced by means including a spreader 21 connected to the back legs 15 and 16 and by connecting means such as chains 22 associating the front and back legs, substantially as shown, these chains also serving to maintain the 15 annulus at a predetermined angle of inclination with respect to the surface upon which the device rests. It will be observed that, if desirable, the annulus can be raised or lowered with respect to the surface upon which the structure 20 rests without altering the angle of inclination of said annulus with respect to said surface.

Referring now to Figs. 1 and 2, it will be observed that the annulus 10 is provided with a plurality of visible indicating means, preferably 25 miniature lamps, certain of which are designated at 30, arranged upon same in spaced relationship substantially as shown. It will also be noted that audible indicating means are provided, mounted on said annulus and generally 30 designated by the numerals 31 and 32, the function thereof being hereinafter described. Power supply terminals and manual switching means generally designated at 35, are mounted and arranged on the bottom portion of the annulus, 35 materially as illustrated. The upper portion of the annulus serves to support the score board whereon certain rules of the game are displayed and whereon the score is also visibly displayed. In the preferred embodiment of the invention 40 the score board 20 is supported on the annulus 10 by means including upright members, one of which is indicated by the numeral 38, associated with the board and annulus as illustrated in Fig. 2.

45 The supporting member upon which the hoops rest will now be described, reference being made to Figs. 2, 3 and 4, wherein the details thereof are best illustrated. The member comprises a shape substantially resembling a modified V or U in 50 outline and formed, in the preferred embodiment of the invention, by processes such as die casting. One arm 40 of the shape is attached to and supported by a portion of the annulus as, for example, by means of a flanged portion 41 55 formed at the free end of said member, the other end of said arm being connected by the cross-piece 42 to the hoop receiving member proper 43. The arms 43 is provided with a plurality of V-shaped upwardly projecting parts 45, 46, 47, 60 48, 49 and 50 formed integral therewith, one of the arms of each of said V-shapes being substantially vertical with respect to the member 43 and the other of said arms being inclined toward the front portion 51 of said member, substantially as shown. It will also be observed that near the front end 51 of the member 43 an upright arm 44 is provided, formed integral therewith and extending forwardly to support a visible target indicating means generally designated 65 70 at 80, to be hereinafter described. Adjacent the member 43 on each of the upright arms of the V-shaped members 44, 45, 46, 47, 48, 49 and 50 is provided bushings of electrically insulated material 54, 55, 56, 57, 58, 59 and 60, respectively, 75 around which are positioned the electrically con-

ductive switch elements 64, 65, 66, 67, 68, 69 and 70. It will be observed that each of the switch elements 64, 65, 66, 67, 68, 69 and 70 is electrically insulated from the member 43 and from the members 44, 45, 46, 47, 48, 49 and 50 by means 5 including the insulated bushings 54, 55, 56, 57, 58, 59 and 60, arranged as aforesaid and substantially as shown. Each of the switch elements is electrically connected and wired in electrical circuit with the score indicating means as 10 will be hereinafter described, the current-carrying lines associated with said elements being positioned within hollowed-out portions of the arms 40, 42 and 43 being led to the elements through openings, one of which is designated at 15 53 in Fig. 3 positioned adjacent said element and between the arms of said V-shaped members 45—50 inclusive, the other end of said line leaving the arm 40 through an opening generally designated at 52, from which the lines pass to 20 the visual indicating means hereinafter to be described.

In order to facilitate checking and/or replacement of the wiring within the modified V-shaped casing comprising the arms 40, 42 and 43, it will 25 be noted, referring to Fig. 4, that the modified V-shaped member is formed of a channel stock 61 with fitting cover 62, the cover being held in place by fastening means such as, for example, a plurality of screws, one of which is designated 30 at 63.

The visual target indicating means generally designated at 80 will now be described and comprises a target plate proper 71 attached to a bent end portion 72 of said arm 44 as, for example, by fastening means such as a nut and bolt 73. A miniature electric lamp, comprising lamp socket generally designated at 74, is mounted on said plate 71, substantially as shown, and connected by one lead to the arm 44 and by another 40 lead to a portion of the electric circuit as will be hereinafter described.

As hereinabove alluded to, it will be noted that the arm 43 is maintained in substantially horizontal position with respect to the surface upon 45 which the device rests and although the end portion wherein the visual target means generally designated at 80 is positioned substantially near the center of the annulus 10, the arm 43 is positioned obliquely with respect to the plane 50 defined by said annulus whereby the parts are disposed in relationship substantially as illustrated in Figs. 1 and 2.

In the playing of the game, metallic hoops 55 prefabricated of resilient spring-like electrically conductive material, are employed and are positioned upon the member 43 and associated members whereby said hoops rest between the synclined edges defined by upright and by inclined arms of pairs of members 45, 46, 47, 48, 60 49 and 50, it being understood of course that the switch element 64 mounted on the arm 44 and the electrically conductive casing portion 42 also function in conjunction with these elements. It will be seen then that as a hoop or annulus such 65 as, for instance, the one designated by the numeral 81, when so positioned rests upon one of the inclined arms of the V-shaped members and one of the switch elements, in the particular instance illustrated in Fig. 2, the inclined arm of 70 the member 46 and switch element 65 mounted on the V-shaped member 45 whereby electrical contact is effected between said member 46 and said element 65.

Referring now to Fig. 5, the electrical circuit 75

concatenating the various elements in the device according to the present invention will be described. Lines 100 connected to a source of continuously alternating electric current are fed to the primary of a current transformer, generally designated at 102. The current from the secondary 103 is utilized in actuating the score and visual indicating means. One side of the secondary 103 is connected by means including the line 104 to the frame of the hoop receiving member generally designated at 11 in Fig. 1. It will be seen that each of the inclined arms of the V-shaped elements comprising a serrated hoop receiving member, are connected to the one side of the secondary, that is to say, in the diagram the inclined faces of the members 42, 50, 49, 48, 47, 46 and 45 are connected to the line 104. The lamp 74 is also connected in this leg of the secondary circuit by means including the line 44 and the line 105, the latter being connected to the opposite leg 107 of the secondary through the switch 106, whereby it will be seen that when desired said lamp 74 can be dissociated from said circuit as conditions of use may indicate as preferable. The other line of the secondary, namely the line 107, serves as a common line to the score and visual indicating means as follows: The line 110 connected to said line 107 is connected to the buzzer 32 through the line 111; line 110 is connected to the lamps 129 and 130 through the line 112 common to both sets of lamps; line 110 is connected to the lamps 128 by the line 113 common thereto; likewise the lamps 127 are connected to said line 110 through the line 114 common thereto; the bell 31 and the lamps 126 are connected to the line 110 through the line 115 common thereto and the score indicating lamps 145, 146, 147, 148, 149, 150, 151, inclusive, through the line 116 common thereto. Thus it will be seen that all the electrical score indicating apparatus is at all times connected to one side of the secondary of the power transformer generally designated at 102. Connection is established to the other side of the secondary during the playing of the game by disposition of a metallic hoop upon the serrated hoop receiving member whereby the metallic hoop establishes contact between the synclined edges of the serrations.

Tracing then the circuits of the different serrations in sequence, it will be seen that the serration including the inclined member 45 is connected by means of a metallic hoop to the switch element 64 and thence by the line 164 to the bell 31 and thence to the lamp 148. It will be seen then that the circuit including the bell, lamp and transformer secondary, is completed through the lines and electrical elements 184, 45, 64, 164, 31, 145, 116, 110 and 107. Thus it will be seen that when the metallic hoop rests upon the first serration the bell 31 will be actuated and the lamp 145 will be lighted.

In like manner, a hoop resting upon the inclined surface 46 completes the circuit including the buzzer 32 and the lamp 146 as follows—lines and electrical elements 104, 46, 85, 165, 146, 116, 110 and 107. Thus it will be seen that a hoop resting on the second serration causes actuation of the buzzer 32 and lighting of the lamp 146.

Referring now to the third serration, it will be seen that a hoop resting upon the inclined member 47 will complete the circuit including the power source in lamps 126 and 147 as follows: lines and electrical elements 104, 47, 66, 166, 126a, 147, 116, 110 and 107. Thus it will be seen that

a hoop resting upon the third serration will cause the lamps 126 and 147 to be lighted.

Referring now to the fourth serration, the circuit including the lamps 127 and 148 and the transformer secondary is completed through the following lines and electrical elements: 104, 49, 87, 167, 127a, 148, 116, 110 and 107. Thus it will be seen that a hoop resting upon the fourth serration causes the lamps 127 and 148 to be lighted.

Referring now to the fifth serration, it will be seen that the circuit including the lamps 128 and 149 and the transformer secondary will be completed by a hoop resting upon said serration through the following lines and electrical elements: 104, 49, 68, 168, 128a, 149, 116, 110 and 107. Thus it will be seen that a hoop resting in the fifth serration will cause the lamps 128 and 149 to be lighted.

In like manner a hoop resting in the sixth serration completes circuits as follows: 104, 60, 69, 169, 129a, 100, 150, 116, 110 and 107. Thus it will be seen that the lamps 129 and 150 will be lighted when the hoop rests in said sixth serration.

A hoop resting in the seventh and last serration completes circuits through the following lines and electrical elements: 104, 42, 70, 170, 130, 170, 151, 116, 110 and 107 whereby the lamps 130 and 151 are associated with the secondary of the power transformer generally designated 30 at 102 and thereby lighted.

It is to be noted that during the playing of the game a hoop or a plurality of hoops can rest upon one or several of the serrations formed in the member generally designated at 11 and although the hoops contact with each other, no short-circuit will result inasmuch as they merely serve as switch elements in one side of the line and no potential difference exists between the hoops so positioned upon different serrations in 40 said member. It is also to be observed that during playing of the game, throwing of hoops upon the serrated member, generally designated at 11, and engagement of said hoops therewith will result in movement of said hoops either when 45 originally positioned upon said member or subsequently when struck by other hoops thrown during the course of the playing, whereby the circuit completed through said hoops is intermittently broken thus causing blinking or flashing of the 50 various lamps included in the circuit completed by the moving hoop and also under certain conditions intermittently actuating the audible indicating means.

In the preferred embodiment of the present invention means are provided for electrically illuminating the score board, generally designated at 20, said means including a lamp, generally designated at 180 in Fig. 1, and positioned over, or at least adjacent to, said score board. Referring to Fig. 5, it will be seen that said lamp 180 is supplied with electrical current from the power line 100 through the lines 181 and 182, the last mentioned line having interposed therein a switch 183 for disconnecting said lamp when 65 opposite or exigent.

During the playing of the game the player positions himself a reasonable distance in front of the device and endeavors by tossing or throwing hoops to position same upon the serrations 70 in the member generally designated at 11. It will be seen that under certain conditions the game can be played in substantially total darkness inasmuch as the central target generally designated at 80 can be illuminated by actuation 75

of the switch as hereinabove described, whereby said target or at least the lamp therein is connected with the secondary of the power transformer 102. As the hoops fall in the various serrations of the member generally designated at 11, they actuate the score and visual indicating means as hereinabove described, whereby the various lamps positioned upon the annulus are associated electrically with the secondary of the power transformer 102 and thereby lighted. It will be seen then that not only can scoring be accomplished during playing of the game in substantially total darkness, but also the score will be visibly displayed upon the board generally designated at 20 by the various lamps positioned upon the annulus.

It will also be apparent to those familiar with this art that certain modifications can be made in the device according to the present invention 20 from the embodiment herein illustrated and described without substantial departure from the spirit of the invention as, for instance, the hereinabove described score mechanism can be modified or augmented by including and electrically 25 associating therewith a sign whereon printed matter appears, adapted to be illuminated or otherwise exposed or emphasized in sections as, for instance, by positioning an electric light behind each letter when the sign is made up of 30 a plurality of transparent or at least translucent letters or numerals, whereby as hoops fall into portions of the serrated member, parts of said printed matter are illuminated. It is preferred that all of the printed matter be illuminated by 35 positioning one hoop in each of the several serrations of the central hoop-receiving member. This embodiment of the present invention is of especial value for amusement purposes inasmuch as successive throwing of hoops often causes 40 hoops positioned in certain of the serrations to be moved therefrom, whereby the difficulty of positioning one hoop in each of the serrations is apparent. This effect can be made more pronounced by arranging the scoring system where- 45 by the serrations nearest the player are highest in score value and, accordingly, most desirable to a player endeavoring to make a high score. It will be noted that under these conditions an initially high score obtained by throwing the 50 first or at least one of the first hoops in a game, can be materially altered during the subsequent playing of the game when the total score is the summation of the individual scores made by positioning hoops in certain of the serrations 55 whereby the final score of player is broadly uncertain until the last hoop has been thrown. In other words, the score is highly flexible until all hoops are thrown. The first hoop may fall in a serration of the highest score, for example 60 500, and upon the next throw be moved into the serration scoring 25. Therefore, until the game is completed the player's score is variably from high to low and vice versa.

65 It will, of course, be understood that instead of scores, penalties, forfeits and the like can be imposed or awarded to the players making scores of predetermined value or to players positioning hoops in previously selected portions of the serrated hoop-receiving member.

70 It is preferred that the indicating lights positioned on the annulus and on the score board be of different colors whereby, if preferred, individual players can attempt to light the lights of a particular predetermined or preselected color,

thereby providing a still further modification of the game as hereinabove described.

It is also to be noted that the amusement device according to the present invention is substantially and exclusively a game of skill wherein proficiency is acquired through practice as contrasted to games of chance wherein proficiency is not necessarily predicated upon practice but is largely the result of casual and fortuitous occurrences.

It is to be understood that this improvement is capable of extended application and is not confined to the exact showing of the drawings nor to the precise construction described and, therefore, such changes and modifications may be made therein as do not affect the spirit of the invention nor exceed the scope thereof as expressed in the appended claims.

What is claimed is:

1. An amusement device of the type described comprising a plurality of light hoops formed of electrically conductive material and an essentially upright support, a game board mounted on said support and having a substantially circular opening formed therein adapted to permit passage therethrough of said hoops, a target supported within said opening, electrically actuated score indicating means mounted on said board, means for controlling said score indicating means comprising a substantially horizontally positioned member presenting upwardly extending serrations adapted to receive and cooperate with portions of said hoops, and an electrical circuit associating said serrations and said score indicating means whereby electrical circuits are altered by resting hoops on said serrations and said score indicating means is actuated.

2. An amusement device of the type described comprising a plurality of light hoops formed of electrically conductive material and an essentially upright support, a game board mounted on said support and having a substantially circular opening formed therein adapted to permit passage therethrough of said hoops, a centrally positioned target supported within said opening, electrically actuated visual and audible score indicating means mounted on said board, and means for controlling said score indicating means comprising a substantially horizontally positioned member presenting upwardly extending serrations adapted to receive and cooperate with portions of said hoops, each of said serrations comprising a plurality of isolated electrically conductive elements associated in electrical circuit with said score indicating means whereby electrical circuits are altered by resting hoops on said serrations and said score indicating means is actuated.

3. An amusement device of the type described comprising a plurality of light hoops formed of electrically conductive material, an essentially upright support adjustable in height, consisting of a plurality of cooperating extensible and contractible legs, a game board mounted on said support, disposed in materially upright though slightly inclined position, and having a substantially circular opening formed therein adapted to permit passage therethrough of said hoops, a centrally positioned target supported within said opening, electrically actuated visual and audible score indicating means mounted on said board, and means for controlling said score indicating means comprising a substantially horizontally positioned member mounted on portions of said board presenting upwardly extending serrations

adapted to receive and cooperate with portions of said hoops, each of said serrations comprising a pair of synclined electrically isolated conductive elements associated in electrical circuit with said score indicating means whereby electrical circuits are altered by resting hoops on said serrations thereby establishing electrical circuit between the elements thereof and actuating said score indicating means.

4. An amusement device of the type described comprising a plurality of light hoops formed of electrically conductive material, a supported materially upright though slightly inclined game board having a substantially circular opening formed therein adapted to permit passage therethrough of said hoops, electrically actuated visual and audible score indicating means mounted on said board, a U-shaped member consisting of horizontally positioned extended arms and upright connecting cross piece, said member being mounted adjacent and extending rearwardly of said opening formed in said board and fastened thereto by mounting means connecting said board and the free end of one of said arms, a target mounted on and carried by the free end of the other of said arms and positioned substantially centrally within said opening, and means for controlling said score indicating means comprising a plurality of upwardly extending serrations formed on said target-carrying arm adapted to receive and cooperate with portions of said hoops, each of said serrations comprising a plurality of isolated electrically conductive elements associated in electrical circuit with said score indicating means whereby hoops tossed at said target can rest on said serrations thereby completing electrical circuits causing said score indicating means to be actuated.

5. An amusement device of the type described comprising a game board, said game board having a substantially circular opening formed

therein, a target member carried by said board and disposed substantially centrally of said opening, said target member having a plurality of serrations, and means for electrifying said target member whereby a circuit is closed by a projectile contacting one or more of said serrations.

6. In an amusement device of the type described, a target member comprising a U-shaped element consisting of horizontally positioned extended arms and an upright connecting cross-piece, and a plurality of upwardly extending serrations formed on one of the horizontally extending arms of said U-shaped member for receiving and holding hoops.

7. An amusement device of the type described comprising a game board, a target member associated with said game board, said target member including an arm having a plurality of substantially V-shaped projections formed thereon, one of the legs of each V-shaped projection being substantially vertical and the other leg inclining toward the front of said member, said legs forming electrical contacts of a signal circuit whereby the circuit is completed by a projectile contacting one of said V-shaped projections.

8. An amusement device of the type described comprising a game board, a target member associated with said game board, said target member including an arm having a plurality of substantially V-shaped projections integral therewith, one of the legs of each V-shaped projection being substantially vertical and the other leg inclining toward the front of said member, said vertical legs having a ring of insulating material thereon and electrical conducting switch elements disposed over said insulating material, said target member being electrified whereby a circuit is closed by a projectile contacting one of said switch elements and its associated inclined arm.

MOSES GOLDMAN.
